[73] Assignee: The Gillette Company, Boston, Mass.

[57] CLAIM

[**] Term: 14 Years

The ornamental design for a correction fluid dispenser cap, as shown.

[21] Appl. No.: 817,829

DESCRIPTION

[22] Filed: Jan. 7, 1992

FIG. 1 is a top, left front perspective view of a correction fluid dispenser cap showing my new design;

[52] U.S. Cl. D19/57; D19/48;
D19/56

FIG. 2 is a top plan view thereof;

[58] Field of Search 401/243, 244, 245, 246,
401/247; D19/35, 36, 41-51, 54-58, 81-85

FIG. 3 is a bottom plan view thereof;

[56] References Cited

FIG. 4 is a front elevational view thereof;

U.S. PATENT DOCUMENTS

FIG. 5 is a right side elevational view, the left side
elevational view being a mirror image thereof; and,D. 310,684 9/1990 Ito D19/57
D. 312,391 11/1990 Vitrac D19/51
D. 317,324 6/1991 Chuang D19/57
D. 317,625 6/1991 Ito D19/57
D. 318,294 7/1991 Cho-Kai D19/48

FIG. 6 is a rear elevational view thereof.

The interior of the correction fluid dispenser cap, delineated by the broken line periphery in FIG. 3, forms no part of the claimed design.
